UNITED STATES PATENT OFFICE.

BARNET NEWLAND, OF NEW YORK, N. Y.

DESIGN FOR A WALL BRACKET.

Application filed April 5, 1924. Serial No. 9,163. Term of patent 3½ years.

To all whom it may concern:

Be it known that I, BARNET NEWLAND, a citizen of the United States, and residing at New York city, in the county of New York and State of New York, have invented a new, original, and ornamental Design for Wall Bracket, of which the following is a specification, reference being had to the accompanying drawings, forming part hereof.

The figure is a perspective view of the wall bracket embodying my design.

I claim:

The ornamental design for a wall bracket, as shown.

BARNET NEWLAND.
